UNITED STATES PATENT OFFICE.

CHARLES G. NELSON, OF CHICAGO HEIGHTS, ILLINOIS, ASSIGNOR TO ZOURI DRAWN METALS COMPANY, OF CHICAGO HEIGHTS, ILLINOIS, A CORPORATION OF ILLINOIS.

SELF-SUPPORTING WINDOW SASH.

Application filed March 29, 1926. Serial No. 98,187.

My invention relates to a metal window sash, and more particularly to a structure which may be affixed to a supporting surface perpendicular to the plane of the glass, 5 without an auxiliary supporting member having a surface parallel with the pane.

In the accompanying drawings, Figure 1 is a cross-section through a sash embodying one form of my invention, and Fig. 2 is a 10 view similar to Fig. 1 showing an alternative shape of one of the glass clamping members.

In Fig. 1 there is shown a supporting member 10 which forms a part of the frame 15 surrounding the window opening. This supporting member has a surface 11 substantially perpendicular to the plane of the glass pane 12.

The glass is held in place by an inner 20 clamping member 13 and an outer clamping member 14. The inner clamping member has a flange 15 adapted to lie against surface 11 of supporting member 10. An upright portion 16 of clamping member 13 extends from the inner side of flange 15 in a direction generally parallel with the plane 25 of pane 12. In the structure shown, there is an offset portion 17 adjacent the surface of supporting member 10. A flange 18 extends from the edge of portion 16 to the inner side of the glass, and a flange 19 extends from the edge of flange 18 towards member 10 and is adapted to lie against the inner surface of the sheet of glass.

35 A bracket member 20 fits within inner member 13 between the flanges thereof. This bracket member may be like that shown and claimed in my patent on metal window sash #1,570,702, granted January 26th, 1926, or 40 of any other suitable construction. The essential features are that it shall fit within the inner sash member so as to stiffen the sash member, and that it shall have a passage opening towards the outer sash member.

45 In accordance with the present invention this bracket member has an extended flange 21 extending forward from its bottom portion and lying upon flange 15. A screw 22, or other suitable fastening device, passes 50 through flanges 21 and 15 and attaches them securely to member 10.

Outer clamping member 14 has a flange 23 at its upper edge substantially perpendicular to the glass sheet and a flange 24 55 lying against the outer surface of the glass

and extending from flange 23 towards supporting member 10. At the lower edge of the outer clamping member there is an inwardly turned flange 25. Preferably, there is a bead 26 along the edge of the outer 60 clamping member, which rests against surface 11 and is adapted to contact the outer edge of flange 15. Flange 25 extends upwardly and inwardly from bead 26. Flange 25 may lie against the upper side of flange 65 15, but preferably is spaced slightly away therefrom.

An L-shaped draw-plate has the end of one arm 27 resting against flange 24 and the other arm 28 extending into the passage 70 within bracket member 20. The angle of the draw-plate is connected to flange 25 of the outer clamping plate. In the structure shown, the connection is made by a small portion 29 of flange 25 being turned upward 75 through an opening 30 in the draw-plate. Arm 28 is provided with a surface 31 at an angle to surface 11. A screw 32 working within a bushing 33 in bracket member 20 is adapted to contact surface 31 and thereby force arm 28 inward until the outer 80 clamping member is brought into suitable engagement with the glass, and then to retain the draw-plate in the position to which it is thus adjusted.

The structure above described may be used at the bottom, sides or top of a pane of glass. When used at the bottom of a pane of glass, a block, not shown, will be provided for supporting the pane of glass. Similar blocks 90 may be provided at the sides and the tops of the glass if desired.

In assembling this structure, the inner clamping member, with brackets 20 suitably positioned at spaced intervals therealong, is 95 placed against surface 11 and attached to supporting member 10 by screws 22 through flange 21 of each bracket 20 and the subjacent flange 15 of inner clamping member 13. Thereafter the glass sheet is placed in position within the opening and rested against flange 19. Then outer clamping member 14, with the draw-plates attached thereto at suitable intervals, is placed in position with bead 26 against surface 11 and 100 flange 24 against the outer surface of the glass. Arms 28 then enter passages in the corresponding brackets 20, and operation of screws 32 produces the desired amount of 105 resilient pressure upon flanges 24 and 25 110

and maintains the draw-plate in position to continue this resilient pressure. It will be readily seen that bracket members 20 will sufficiently stiffen and support inner clamping member 13 while the draw-plates will hold the outer clamping member 14 in adjusted position.

The structure shown in Fig. 2 is the same as that shown in Fig. 1, except that the configuration of the outer clamping plate is changed, and the cooperating arm of the draw-plate is correspondingly modified to fit within the outer clamping member. The parts in Fig. 2 are designated by the same reference characters as the parts in Fig. 1, with the letter "a" added; and as the relation of the parts and the operation thereof is the same as in Fig. 1, a detailed description of the sash shown in Fig. 2 is unnecessary.

It will be readily understood that various changes may be made in the structure of the various parts and in their connection with each other, within the scope of the appended claims, which define my present invention.

What I claim is:

1. In a window sash, a rear clamping member and a front clamping member, a bracket member in interlocking engagement with the rear clamping member and having a passageway therein opening towards the front clamping member, a draw-plate connected with the front clamping member and having an arm extending into said passageway, means connected with said bracket for drawing said arm into said passageway, a supporting member having a surface beyond and perpendicular to the plane of the glass in said sash, a flange extending forwardly from the rear clamping member, across the plane of the glass, and adapted to lie against said surface, a flange extending from said bracket and overlying the first mentioned flange and means securing said flanges to said supporting member.

2. In a window sash, a supporting member beyond one edge of the glass and having a surface substantially perpendicular to the plane of the glass, a clamping member having a bottom flange adapted to lie against said surface and a glass engaging flange spaced from and substantially perpendicular to said bottom flange, a bracket within said clamping member having a portion adapted to rest against said glass engaging flange and having a bottom flange adapted to lie upon the bottom flange of the clamping member, and a screw passing through said bottom flanges and attaching them to said supporting member.

3. In a window sash, a supporting member beyond one edge of the glass and having a surface substantially perpendicular to the plane of the glass, an inner clamping mem-

ber and an outer clamping member, said inner clamping member having a flange lying against said surface, a bracket within the inner clamping member having a passage opening towards the outer clamping member and having a flange overlying the said flange of the inner clamping member, a screw attaching said flanges to said supporting member, an arm connected with the outer clamping member and entering said passage, and means connected with the bracket for securing said arm in place therein.

4. In a window sash, a supporting member beyond one edge of the glass and having a surface substantially perpendicular to the plane of the glass, an inner clamping member and an outer clamping member, said inner clamping member having a flange lying against said surface, a bracket within the inner clamping member having a passage opening towards the outer clamping member and having a flange overlying the said flange of the inner clamping member, a screw attaching said flanges to said supporting member, an arm connected with the outer clamping member and entering said passage, and means connected with the bracket for drawing said arm into said passage and securing it in place therein.

5. In a window sash, a supporting member beyond one edge of the glass and having a surface substantially perpendicular to the plane of the glass, a rear clamping member having a flange along one side adapted to engage the glass and a flange along the other side adapted to lie against said surface, a bracket member interlocking with said clamping member and having a passage opening towards the front clamping member, the bottom wall of said passage overlying the second said flange of the clamping member and having a forward extension from its front edge, a screw passing through the forward extension of said bracket and the last mentioned flange of said clamping member and securing them to said supporting member, a front clamping member, an arm connected to said front clamping member and extending through said bracket opening into the passage in said bracket, and means connected with the bracket for securing said arm in place.

6. In a window sash, a supporting member beyond one edge of the glass and having a surface substantially perpendicular to the plane of the glass, a rear clamping member having a flange along one side adapted to engage the glass and a flange along the other side adapted to lie against said surface, a bracket member interlocking with said clamping member, having a passage opening towards the front clamping member, and having a flange extending from its front side and overlying the second said

flange of the clamping member, a screw passing through the last said flanges of said bracket and said clamping member and securing them to said supporting member, a front clamping member having a rearwardly extending bottom flange, an arm connected to said bottom flange and extending through said bracket opening into the passage in said bracket, said arm and bottom flange, at the point where they are connected, being spaced from the flanges of the bracket and clamping member which are secured by said screw and means for drawing said arm into said bracket and securing it in position therein. 10

5

In testimony whereof I have hereunto signed my name to this specification. 15

CHARLES G. NELSON.
